CATHODE FOR ELECTRICAL DISCHARGE DEVICES

Carl J. R. H. von Wedel, Berlin, Germany, assignor to Electrons, Inc., a corporation of Delaware

Application May 9, 1929. Serial No. 361,652

19 Claims. (Cl. 250—27.5)

My invention relates generally to cathodes for discharge devices on which an electron emissive substance is used, and more particularly to filamentary or directly heated cathodes for electric discharge tubes. The features of the invention offer particular advantages in connection with large current and high potential discharge devices, as in heavy duty rectifier tubes, but may be applied with advantage to tubes having those 10 characteristics usual for radio receiving and like amplifying systems.

Since the beneficial results of my invention are better emphasized in connection with a heavy duty gas-filled rectifier tube I hereinafter describe my invention with respect thereto, but I do not wish to be limited by this choice to such devices alone for, as mentioned hereinbefore, my invention is applicable to space discharge tubes in general utilizing an electron emissive cathode. 20 Heretofore in the prolonged use of discharge tubes it has been noted that the space current decreases with use, and at a more rapid rate of decrease when operated at high potential.

Some of the causes of decrease in space current with use of emissively coated cathode tubes are discussed and procedures for improvement are presented, in Patent No. 1,817,636, issued August 4, 1932 to Friedrich Meyer and Hans Joachim Spanner.

30 In addition to the causes pointed out in said patent for the waning of space current with use I have found that when operating with high currents and high potentials the emissive coatings undergo severe physical disturbances even to the effect of loosening and tearing portions of the emissive coating from its support; and also that arcing effects may occur and be most destructive to the coating and its support.

40 It is the object of the present invention to materially eliminate any loosening of the coating from the core or filament, and effects of such loosening, even though the tube may be operated at such potentials that arcing occurs at times between the anode and the cathode.

45 A further object of my invention is to so proportion and arrange the cathode core and coating thereon that when arcing between the electrodes occurs, which arcing normally results in quick destruction of the cathode due to increased emission because of overheating at the point where arcing occurs, the point of arcing will become electronically inert so that further destruction at the point will not occur.

55 Further objects will appear as the description

of the drawing forming a part hereof is developed and in which,

Figure 1 is a perspective view of a segment of my improved cathode,

Figures 2, 3 and 4 illustrate the manner in which the core of my improved cathode is constructed, and

Figure 5 illustrates the action of my improved cathode co-operating with an anode in a rectifier tube.

Referring to Figure 1, the cathode comprises a core 1 having a helical rib 2 between the spaced turns of which is embedded a filling 3 of an electron emissive compound preferably one of the electron emissive compounds described in the patent hereinbefore mentioned. The metals of the core and of the helical rib, at least the surface portions thereof, and the emissive compounds used thereon, are preferably chosen for the favorable influence of the core materials on the durability and continued emissivity of the compounds and their resistance to the destructive effects of ionic bombardment, so that the surface metal and its corresponding emissive material for a cathode structure may be, for example, any one of the following combinations:

Aluminum—Barium aluminate; Zinc—Barium zincate; Nickel—Barium nickelate; Cobalt—Barium cobaltate; Chromium—Barium chromite; Zirconium—Barium zirconate; or with these compounds singly or as mixtures interchanged with the metals; or those emissive compounds in which the barium has been replaced by any one of the alkaline metals; or those emissive double metal compounds in which the element oxygen has been replaced by sulphur, nitrogen, fluorine, carbon or arsenic.

With reference to Figures 3 to 5, I limit my description merely for the sake of brevity to a cathode the surface of which is nickel and the emissive compound thereon is barium aluminate, but it is to be understood that other metals may be substituted for nickel preferably those metals which are capable of forming amphoteric compounds less acid than titanic acid, and another emissive compound used in conjunction therewith, without departing from the scope of my invention as defined in the appended claims.

Referring to Figure 2, I employ a filamentary core 4 of sufficient size to carry the heating current for the particular design of tube. I coat this core 4, which may be tungsten or platinum, with a surface 5 of another metal such as nickel by any of the usual electro-plating or other processes. Upon this coated core, I wind a helix

having preferably a pitch equal to one and one-half times the diameter of the wire 6 of the same or a similar metal, the resultant product being shown in Figure 3. I then treat the structure of Figure 3 in an electrolytic or other bath containing one of the above mentioned metals, such as nickel, so that there is produced a coating or plating over the entire structure, with the result that the turns of the helix 6 are metallically and conductively connected to the surface 5 as shown at 7 in Figure 4. (See Figs. 1 and 5.) In this manner I have produced a helical "dove-tail" groove about the core in which I place the filling of emissive compound 3, for example, barium aluminate, filling the "dove-tail" groove substantially to the outer diameter of the helix 6.

When this type of cathode is used with a closely associated anode 8 having high potential, the emissive coating being securely held within the "dove-tail" groove of the cathode, there is little possibility of the coating being loosened and torn from the core.

This type of cathode has particular advantages in gas filled rectifier tubes. The electron cloud around the cathode neutralizes the ions of the discharge to prevent ionic bombardment, and the neutralizing is most effective because such a cathode arrangement has a very large effective emitting surface, enhanced by the fact that the emissive coating continuously creeps over the surface of the helix 6 maintaining an undulated effective emissive surface.

Further, should an arc occur between the anode and the cathode, Fig. 5, such arcing will occur between the helix 6 and the anode 8 with the result for instance that, a portion of the helix 6 will be burned away as illustrated at 9. Even though the cross-section of the cathode proper at this point is reduced by this action, it is still greater than the cross-section of the core proper at a point between the turns of the helix 6, so that no "hot-spot" is produced on the cathode by reason of reduction of current carrying cross-sectional area. The creeping characteristic of the emissive coating during operation soon covers over the injured spot so that the original characteristic emission from this portion ensues.

Should the arcing continue for a sufficient length of time that a portion of the cathode is pitted as shown at 10 sufficiently deep to penetrate to the core 4, the ionic bombardment of the gas upon the exposed core metal, together with the creeping of the emissive coating thereover, will form a non-emitting coating at 11 for the reasons set forth in the aforementioned patent, so that at the temperature at which such a cathode is designed to operate, usually about 800° C., emission at this point stops even though this point is relatively hotter than the rest of the cathode. In this manner the destruction of the cathode at this point is stopped. Since in general these spots, if occurring, are of small area as compared to the rest of the cathode the remaining emissive surface will easily provide the necessary emission for continued operation of the tube with but little decrease in space current.

While I have described herein a specific emissive cathode structure in which I have utilized the metals tungsten and nickel, and prefer to use thereon as electron emissive substances certain compounds such as compounds of the highly electropositive metals in the form of zincates, chromites and zirconiates or other materials such as the fluorides of these metals and those previously mentioned, and specifically barium

aluminate, it is to be understood that other metals and other emissive compounds, such as those proposed by Wehnelt, or barium oxide, strontium oxide and calcium oxide, or mixtures thereof, may be used without departing from the spirit of my invention as defined in the claims appended hereto.

Having thus described my invention what I claim is:

1. In a cathode structure, the combination of a cylindrical core, a helix of wire wound upon said core, a metallic junction between the wire and said core whereby said wire is incorporated integrally upon said core, and an electron emissive substance between the turns of said helix.

2. In a cathode structure, the combination of a core of highly refractory metal, a coating of a metal upon said core, capable by chemical conversion of forming an "amphoteric compound" less acid than titanic acid, a helical rib of said metal integral with said coating and surrounding said core, and an electron emissive material between the turns of said helical rib.

3. In a cathode structure, the combination of a core of highly refractory metal, a coating of nickel upon said core, and a helical rib of nickel metallically joined to said coating.

4. In a cathode structure, the combination of a core of highly refractory metal, a coating of nickel upon said core, and a nickel wire helically wound over said coating and metallically integral therewith, said nickel wire forming a helical "dove-tail" groove around said core.

5. In a cathode structure, the combination of a core of tungsten, a plating of nickel upon said core, a nickel wire helically wound upon said core and metallically joined to said plating, and an electron emissive compound between the turns of said helix.

6. In a cathode structure, the combination of a core of highly refractory metal, a nickel wire helically wound upon said core and metallically integral therewith, an electron emissive material including barium nickelate between the turns of said helix.

7. The process of production of a cathode structure which comprises plating a core of tungsten with metallic nickel, winding a helix of nickel wire upon said plating, immersing said core and said helix in a bath containing nickel, by electrolysis metallically joining said helix to said plating and filling in the space between the turns of said helix with an electron emissive material which reacts with said nickel to form barium nickelate.

8. In a cathode structure, the combination of a refractory metal core, a coating of metal upon said core which by chemical conversion forms an amphoteric compound less acid than titanic acid, and a helical rib of a similar metal upon said coating and metallically joined thereto.

9. In a cathode structure, the combination of a core of refractory metal, a coating of metal upon said core capable of forming by chemical conversion an amphoteric compound less acid than titanic acid, a helical rib of said metal integral with said coating, and a compound of a highly electropositive metal capable of forming by chemical conversion a double metal compound with said coating metal the said compound being disposed between the turns of said helix.

10. In a cathode structure, the combination of a core of refractory metal, a plating of metal upon said core, said metal being capable by chemical conversion of forming an amphoteric com-

- 5 pound less acid than titanic acid, a helical wire of said metal wound upon said plating and electrically joined thereto, and an electron emissive compound containing a metal capable of forming by chemical conversion an amphoteric compound less acid than titanic acid, said emissive compound being disposed between the turns of said helix. 86
- 10 11. In a cathode structure, the combination of a core containing, at least on its surface, a metal capable of forming by chemical conversion an amphoteric compound less acid than titanic acid, a helical wire of said metal wound upon said core and electrolytically joined thereto forming a helical dove-tail groove around said core, and an electron emissive compound, capable of forming a double-metal compound with said metal on the core surface, disposed within said dove-tail groove. 85
- 15 12. The method for making a cathode structure which comprises coating a metal core with another metal, winding a helix of wire over said coating, electrically joining said helix to said metal coating, and applying a thin coating of electron emissive material to the outer portions of the helix and a thick coating thereof to the core coating and helix between turns of the latter. 90
- 20 13. The method for making a cathode structure which comprises plating a refractory core with a metal, winding a helix of wire upon said plating, and electrically joining said helix to said plating with an additional plating of said metal on both core and helix. 95
- 25 14. In a filamentary cathode structure, the combination of a metallic core, a series of metal ribs upon said core, a metallic junction between the ribs and the core whereby said ribs are incorporated integrally upon the core, and an electron emissive substance between said ribs. 100
- 30 15. In a cathode structure, the combination of a refractory core, a coating of nickel on said core, a metal wire helically wound on the said core, means for maintaining a metal to metal contact between each turn of the wound wire and said coating, and a substance of electron emitting capacity applied to the said wire. 105
- 35 16. In a cathode structure, the combination of a core at least the outer surface of which is nickel, a metal wire helically wound on said core with each turn of the wire forming with the nickel surface a permanent metallic contact having a lower electrical resistance than a turn of the wound wire, and a substance of electron emitting capacity applied to the said wire. 110
- 40 17. In a cathode structure, the combination of a core of a metal capable of forming by chemical conversion an amphoteric compound less acid than titanic acid, a wire of a similar metal helically wound on the said core and metallically joined thereto for at least a portion of each turn of the wound wire, and a substance of electron emitting capacity applied to the wire. 115
- 45 18. In a cathode structure, the combination of a filamentary core having a surface of nickel, a series of nickel ribs upon said surface and metallically joined thereto, and an electron emissive substance between said ribs. 120
- 50 19. In a cathode structure the combination of a core having a metal layer for its outer portion, said metal being capable of forming by chemical conversion an amphoteric compound less acid than titanic acid, a metal wire helically wound on said metal layer, means for metallically connecting the turns of said wire to the surface of said metal layer, and a substance of electron emitting capacity applied to said wire. 125
